[57] CLAIM

The ornamental design for a combined torpedo level and peripheral angle measuring device, as shown and described.

DESCRIPTION

FIG. 1 is a front perspective view of a combined torpedo level and peripheral angle measuring device showing my new design;

FIG. 2 is a top plan view thereof, the bottom plan being identical thereto but without the sight opening;

FIG. 3 is a front elevational view thereof, the rear being identical thereto;

FIG. 4 is a left side elevational view thereof, the right side being a mirror image thereto.

FIG. 1

FIG. 2

FIG. 4

FIG. 3
